UNITED STATES PATENT OFFICE.

WALTER REENSTROM, OF CHICAGO, ILLINOIS.

PROCESS OF FORMING HOODS AND APRONS FOR VENTILATORS.

1,424,945.

Specification of Letters Patent. Patented Aug. 8, 1922.

Original application filed May 31, 1917, Serial No. 172,016. Divided and this application filed July 14, 1919. Serial No. 310,633.

To all whom it may concern:

Be it known that I, WALTER REENSTROM, a citizen of the United States, and a resident of the city of Chicago, county of Cook, 5 and State of Illinois, have invented a certain new and useful Process of Forming Hoods and Aprons for Ventilators, of which the following is a specification.

My invention relates to a process for forming 10 hoods and aprons for ventilators designed for use upon house-tops and the like, whereby the same are easily and economically manufactured, waste of material being reduced to a minimum, the present application 15 being a division of my application for ventilators, filed May 31, 1917, Serial No. 172,016.

Other objects will appear hereinafter.

The invention will be best understood by 20 reference to the accompanying drawings forming a part of this specification, and in which,

Fig. 1 is a top plan view of hood forming sections.

25 Fig. 2 is a top plan view of a sheet-metal blank, illustrating the method of cutting the same in the formation of the hood and aprons embodied in the ventilator.

Fig. 3 is a vertical sectional view of a 30 ventilator embodying my invention.

Fig. 4 is a top plan view of a sheet used in the ventilator.

Fig. 5 is a transverse sectional view of the device shown in Fig. 3.

35 The preferred form of construction, as illustrated in the drawing, comprises an outer tubular member consisting of a plurality of telescopic tubular sections 6. Said sections are rigidly connected at their points 40 of overlapping by rivets 6'. Arranged within said tubular member is a plurality of spaced, longitudinally extending reinforcing bars or straps 7, which are rigidly connected with the sections 6 by the before mentioned 45 rivets 6'. The upper end portions of bars 7 are rigidly connected with the upper edge portion of the uppermost section 6 by rivets 7'.

Arranged at and spaced directly over the 50 upper end of said tubular member is a conical hood, which is supported by the upper ends of bars 7, which are extended upwardly in order to constitute supports therefor. The hood is formed of two semi-circular sections 55 8 and 8', the edges of which are overlapped,

said edges being notched as at 9 to allow aforesaid overlapping, as clearly seen in Fig. 1. Said overlapping edge portions of said hood sections are rigidly secured together by rivets 9'. It will be noticed in Fig. 1 60 that the section 8 overlaps the section 8' for a distance equal to one half of the diameter and underlaps section 8' a similar distance.

Arranged at the upper edge of each section 6 is an annular downwardly and outwardly inclined apron 10, secured to said sections by means of the rivets 7' and 6'. Openings 11 are formed at the upper ends of each section 6 below the aprons 10 through notching or cutting away the upper edge 70 portions of said sections, as clearly seen in Fig. 3 and Fig. 4. The openings 11 do not extend below the lower edges of the aprons 10, this arrangement precluding a direct draft into said openings, which would otherwise result did said openings extend below the lower edges of said aprons.

In the manufacture of the hood composed of the sections 8 and 8', and in the manufacture of the aprons 10, a rectangular flat 80 blank of sheet metal is employed, as seen in Fig. 2. Said blank is cut along two spaced concentric lines 12 and 13, one half of the hood being formed by the semi-circular portion within the line 12, and one half of one 85 of the aprons being formed by the arcuate strip 10 which is included between the lines 12 and 13. With this process or method of construction, only the corner portions 14 will be wasted. Concentrically arranged 90 within the tubular member of the ventilator is a smaller pipe 15 rigidly held in position by means of arms 16. The upper end of pipe 15 is closed and provided with lateral openings 17, said openings 17 being preferably arranged in substantially the same horizontal plane as the lowermost openings 17. The tubular pipe made up of the sections 6 which surround the pipe 15 is prolonged at the lower end, so as to allow both 100 it and the pipe 15 to pass into and communicate with the interior of the building with which the device is used, for ventilating purposes.

A ventilator of the construction set forth 105 is extremely strong and durable and may be manufactured at a low cost, particularly due to the method of forming the constituent parts of the hood.

While I have illustrated and described the 110

preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope of the appended claim.

10 Having described my invention, what I claim as new and desire to secure by Letters Patent, is:

A method of making ventilator parts from separate sections by cutting blanks for half 15 a hood and half an apron, said blanks being cut from the same piece of material by cut-

ting along two concentric lines having diameters coincident with one of the edges of the piece of material in one operation, forming the blank for half the hood into a conical shaped half hood section and flaring a portion of the blank for the half apron forming a half apron section, and joining other similar parts therewith to provide a complete ventilator hood and apron. 20 25

In testimony whereof I have signed my name to this specification in the presence of two subscribing witnesses.

WALTER REENSTROM.
